UNITED STATES PATENT OFFICE.

JOHN LEXOW, OF TOMPKINSVILLE, NEW YORK.

TOY.

No. 905,085.

Specification of Letters Patent. Patented Nov. 24, 1908.

Application filed February 6, 1908. Serial No. 414,543.

To all whom it may concern:

Be it known that I, JOHN LEXOW, of Tompkinsville, in the county of Richmond and State of New York, have invented a 5 certain Toy, and do hereby declare that the following is a full and exact description thereof.

The object of my invention has been to provide a toy which shall be adapted for 10 playing the game known as "basket-ball"; and to such ends my invention consists in the toy hereinafter specified.

In the accompanying drawings Figure 1 is a side elevation of a toy embodying my 15 invention; and Fig. 2 is a rear elevation of Fig. 1.

In carrying my invention into practice I provide a base A having near one end a post B, whose upper end carries a bracket C in 20 the form of a horizontal ring, the bracket being preferably formed of wire, and having its two ends embedded in the post. A basket C' hangs from the bracket C. A ball D is provided and the object of the game is 25 to throw the ball into the basket. The ball is preferably secured by a cord E to the base.

In order to throw the ball into the basket I provide the following mechanism. A bracket F is secured to the base at or near 30 the end opposite to the post, and such bracket preferably has a vertical slot formed therein, in which is pivoted a lever G, the lever being pivoted on a pin H fastened on the bracket. The forward end of the lever 35 is, in the particular embodiment chosen for illustration, bent downward to rest upon the base from which it rises to support a cup I on its free end. The rear end of the lever has a surface K which is adapted to be 40 struck by the finger, and has a tail L that is adapted to strike against some fixed object to stop the lever in a particular position, as later described. The lever may be arrested, either by a table upon which the base rests, 45 or, as I prefer, by a projection M extending rearward from the table, the projection passing through a slot in the bracket, and a block N being fastened on top of said projection to bear against the rear face of the 50 bracket. This construction permits the bracket to be made of wood, and yet to be firmly supported. The lever is preferably somewhat loose upon its pivot, for a purpose to be described.

In the operation of my toy, the ball is 55 placed in the cup, and the lever is struck with the finger and depressed until its tail L is arrested. The ball is thrown up by this action, and, of course, continues its flight after the lever is stopped. The lever, the 60 cup, the tail and the block N are so proportioned and positioned relative to each other that the lever is arrested while its arc of movement is directed forward as well as upward, thus causing the ball to be thrown in 65 a general direction toward the basket. The ball will be thrown into the basket if the lever is struck with just the requisite force, but no more, to cause its trajectory to pass into the basket, and if the lever is aimed right in 70 a lateral direction. If the lever is struck too hard, the ball will pass over the basket, and if it is not struck hard enough it will pass under it. If the lever is swung to either side of a line toward the basket (as is permitted 75 by its looseness on its pivot), the ball will not enter the basket. There is thus enough skill required to make the game interesting, and yet not enough to make it so difficult as not to be interesting. I have found by experiment that unless the lever is arrested by 80 striking some fixed part, the difficulty of throwing the ball into the basket is so great as to make the game almost impossible, and therefore uninteresting. For instance, if the 85 lever be not thus stopped, the ball may be thrown straight up into the air, or it may be thrown backward over the lever in a direction away from the basket. Therefore, the arresting of the lever by its striking a fixed 90 stop is a very important feature of the invention.

I claim:

1. A toy, consisting of a base, a support rising from said base, a basket carried by 95 said support, a bracket on said base, a horizontal transverse pivot carried by said bracket, a lever mounted on said pivot, a cup on the end of said lever nearest said support, a tail formed on the opposite end of 100 said lever, and a stop so located as to arrest the lever while the cup is moving toward the basket.

2. A toy, consisting of a base, a support rising from said base, a basket carried by 105 said support, a bracket on said base, a horizontal transverse pivot carried by said bracket, a lever mounted on said pivot, the

engagement between said lever and said bracket being loose so as to permit lateral movement of the lever, a cup on the end of said lever nearest said support, a tail formed
5. on the opposite end of said lever, and a stop so located as to arrest the lever while the cup is moving toward the basket.

In testimony that I claim the foregoing I have hereunto set my hand.

JOHN LEXOW.
